DENTAL DEVICE

William J. Kiff, Buffalo, N. Y.

Application October 2, 1941, Serial No. 413,309

1 Claim. (Cl. 15—138)

This invention relates to dental devices and more particularly to improved methods and means for packaging and displaying and using liquid dentifrices and means for applying the same to the use intended thereof.

One of the objects of the invention is to provide an improved combination container-dispenser device for liquid dentifrices. Another object of the invention is to provide an improved form of self-contained reservoir type toothbrush. Another object of the invention is to provide an improved combination dentifrice container and dispensing toothbrush and cover device therefor, whereby the combination unit is adapted to be displayed and otherwise handled in an improved manner in connection with the merchandising and actual use thereof. Other objects and advantages of the invention will appear from the specification hereinafter.

In the drawing:

Fig. 1 is a side elevation of a liquid dentifrice container element of the combination of the invention;

Fig. 2 is an elevation of a toothbrush dentifrice-dispenser device of the invention;

Fig. 3 is an elevation, with portions broken away and shown in section, of elements of Figs. 1 and 2 when arranged in assembled relation; and

Fig. 4 is a view similar to Fig. 3 of another form of dentifrice container-dispenser device of the invention having mounted thereon a protective cover member which is shown in section.

The invention is illustrated in the drawing in connection with a container for a liquid dentifrice which is designated at 10 as comprising a flat bottomed small neck bottle formed of glass or any other suitable material. The neck portion of the bottle 10 is exteriorly threaded at 12 so as to be adapted to engage an interiorly threaded cap 14 in liquid sealing relation, as illustrated in Fig. 1. The dentifrice dispenser device is illustrated in Figs. 2 and 3 as comprising a toothbrush-like member having a reduced shaft portion 16; an enlarged head portion 18 carrying bristles 19; and an enlarged opposite end socket portion 20. The socket portion 20 is bored and threaded so as to adapt the member to be mounted upon the container 10 in rigid and liquid-tight connected relation, as illustrated by Fig. 2; and the shaft and head portions 16—18 of the member are interiorly bored as indicated at 22 so as to be adapted to convey liquid dentifrice from the container 10 into the head 18 for discharge at the base of the bristle members 19.

The bore 22, is so dimensioned and arranged as to normally prevent free flow of the liquid dentifrice therethrough under the force of gravity alone. That is, the bore 22 is of relatively small cross-sectional area so that a capillary-type conduit is thus provided through which the dentifrice may be forced to flow when the device is shaken. Thus, the arrangement provides for flow of dentifrice only when desired. As a further dentifrice flow control feature the enlarged end portion 20 of the dispenser member is formed with an air-inlet conduit 24 (Fig. 3) which is adapted to convey air from exteriorly thereof into the interior of the socket end portion 20. However, the conduit 24 is arranged to terminate at its inner end in registry with the neck end wall of the container 10 when the container and dispenser elements are relatively adjusted into rigid screwed connection. Thus, when the dispenser is tightly screwed upon the container 10 the conduit 24 will be closed, but when the dispenser is unscrewed slightly relative to container neck the conduit 24 will thereby be automatically opened so that air may be freely drawn into the interior of the device to equalize atmospheric pressures exteriorly and interiorly thereof so that there will be no interference to flow of dentifrice through the bore 22 for the purpose intended.

Thus, it will be understood that a particularly convenient form of automatic valve is thus provided in conjunction with the dispenser-container combination unit, whereby without use of complicated moving parts and the like a conveniently manipulable valving arrangement is provided. It will also be appreciated that due to the flat bottom wall form of the container 10 and the arrangement for rigid connection of the dispenser member upon the container member when adjusted to air conduit-closed position, the combination unit is adapted to be placed in upright position while resting upon the flat bottom of the container 10 in such manner that the head and bristle portions of the dispenser are thereby supported away from possible contaminating contact with other objects. Consequently the device is particularly suited to be set in upright position upon a medicine cabinet shelf or the like between uses, for utmost convenience to the user.

As illustrated in Fig. 4, it is contemplated that the socket end portion 20 of the dispenser member may be exteriorly threaded as at 30 so as to be adapted to engage in screw threaded relation thereon the lower end portion of a cover tube 32 which may be formed of glass or transparent

plastic substance, or any other suitable material. To facilitate design of the unit so as to minimize the required diametral dimensions of the cover tube 32, the shaft portion 16 of the dispenser member may be somewhat offset (as shown) from the center of the socket portion 20 away from the direction of the bristles 19. In any event the dispenser will be interiorly bored as indicated at 22. An air inlet conduit 36, for a purpose similar to that of the conduit 24 of Fig. 3 is also provided in the socket portion 20 of the dispenser, but the conduit 36 is preferably disposed to emerge adjacent the back face portion of the brush shaft 16. Hence, when the dispenser is loosened relative to the container to open the conduit 36 and shaken so as to force dentifrice outwardly into the bristles 19, the open conduit 36 will be at the back at the brush member and therefore less liable to accidentally conduct liquid dentifrice towards the exterior of the dispenser handle portion. Thus, the device is of substantially leak-proof character.

It will be understood that the invention provides an improved combination device for storing and dispensing liquid dentifrices, and for protecting the unit against contamination between uses. Also it will be understood that when the combination unit is provided with a cover member as illustrated at 32 (Fig. 4) it is particularly adapted to be transported and displayed for merchandising purposes as a compact dirt-proof package of mechanically simple construction and pleasing external design. When the dispenser is tightly screwed upon the container 10 the air conduit is thereby automatically shut off and thus the unit may be handled and transported as in connection with normal transportation and merchandising handling without fear of leakage of the dentifrice from the unit. However, if preferred, a simple paper disc or the like may be originally inserted between the outer end of the container bottle neck and the inner end of the dispenser socket portion so as to positively seal

the neck opening of the container 10 prior to preparation of the unit for actual use of the contents thereof. Thus, the purchaser may originally unscrew the dispenser from the container and remove the sealing disc, and from thenceforth dispense the contents of the container as needed in the manner described hereinabove.

It will be understood that only a limited number of forms of the invention have been shown and described in detail, but it will be apparent to those skilled in the art that the invention is not so limited but that various changes may be made therein without departing from the spirit of the invention or the scope of the appended claim.

15 I claim:

In combination, a liquid dentifrice container having a cylindrical outlet neck portion externally threaded, and a dentifrice dispensing tooth brush comprising a hollowed shaft portion having a discharge vent and tooth brushing bristles extending from one end thereof and an enlarged cylindrical collar portion at the other end thereof adapted to be screwthreaded upon said container neck portion in fluid sealed connection relation, said collar portion having an atmosphere vent opening extending therethrough from a position at a side exterior portion thereof into covering registry with an end portion of said container neck when said brush member is screwed tightly upon said container, whereby when said brush member is tightly screwed upon said container member said atmosphere vent is closed to prevent unintended passage of dentifrice through said tooth brush hollowed shaft portion and whereby when said tooth brush is partially unscrewed relative to said container said atmosphere vent is uncovered and may be manually selectively covered and uncovered at the exterior end thereof by the user for selectively controlling the flow of dentifrice through said tooth brush shaft portion.

WILLIAM J. KIFF.
